UNITED STATES PATENT OFFICE.

FRANÇOIS RENE MARCEL, OF BROOKLYN, NEW YORK.

HAIR-WAVING TUBE.

Application filed November 8, 1924. Serial No. 748,541.

In producing what is generally called a permanent wave in the human hair it is customary to wind a lock of hair spirally upon a tube or curler after which the hair is tied to the curler or otherwise secured; and then a tube, usually of paper or light cardboard, is placed over the curler and hair, the tube is tied closely to the lock of hair adjacent the head and then an electric heater is placed over the paper tube to generate heat and vaporize the waving material or chemical which has been applied to or near the lock of hair.

My present invention relates first to the paper or cardboard tube which is placed over the curler having the lock of hair wound upon it, and the object of my invention in regard to this tube is to provide a tube which is adapted to be very quickly compressed at the end upon applying a string or tape to close one end of the tube around the lock of hair adjacent the head. These tubes are generally of rather stiff paper or cardboard and more or less time is wasted in compressing the end of the tube about the lock of hair, and while the time consumed in one instance is not of itself so important, nevertheless, in the course of the day it is material because for each head waved there may be anywhere from twelve to forty-eight tubes applied to the head. With the form of tube shown herein the end may be very quickly compressed and it will fold in more or less regular form so that there will be less space between the tube and the hair than heretofore, and therefore there is less likelihood of the hot vapors being directed against the head of the subject.

Another object of my invention is to provide a tube to be inserted within the outer tube and to carry the material or chemical which is used to treat the hair for making the wave permanent. This latter tube is made with indentations or corrugations so that there will be spaces, extending, preferably, longitudinally of the tubes, between the inner and outer tubes in order that when the tubes are dipped into water to moisten the chemical both inner and outer surfaces of the inner tube will be moistened. This results in a quicker moistening of the inner tube and in addition the latter absorbs and holds more moisture than heretofore and there is therefore a more ample supply of water with which to carry on the vaporizing action. Other advantages will be set forth

in the following detailed description of my invention:

In the drawing forming part of this application,

Figure 1 is a perspective view of the outer tube with the electric heater applied to it, the same being shown detached from the hair,

Figure 2 is a longitudinal sectional view through the inner and outer tubes without the electric heater and showing a lock of hair wound upon the curler, the turns of hair being separated to show the interior curler,

Figure 3 is an elevation partly broken away and showing the inner tube,

Figure 4 is a cross section thereof taken on the line 4—4 of Figure 3, and

Figure 5 is an elevation of a sheet of corrugated paper from which the inner tube is made.

A lock of hair 1 is combed out from the head and it is wound upon the winding member 2 commonly called a curler, which may consist of a rod or a perforated tube; and as such devices are well known in the art, detailed description of the curler is not necessary. In Figure 2, I have shown a lock of hair wound around one of the curlers and after it has been wound tightly around the same it is secured at the beginning and end of the winding by tying a string of tape around it or else by means of a clip 3. In this view I have shown the coils of the hair separated in order to show the curler inside, although in practice it is customary to place the coils close together. The outer tube 4 which consists of a cylindrical body of stiff paper or light cardboard, is placed endwise over the curler and lock of hair and the end of the tube adjacent the head is pressed closely about the lock of hair where it is tied by means of a cord or tape 5 as shown in the drawing. These tubes, when sold, are generally cylindrical throughout and there is a loss of time due to the pressing of the inner end around the hair. In the present case a tube 4 is formed at one end with longitudinal indentations or corrugations 6 extending lengthwise of the tube and around its circumference for about an inch or so. These corrugations are formed in the tube by any suitable mechanical means so that the tube, when sold, is in condition to be quickly compressed at one end to fit closely around the lock of hair near the head, and there are smaller air spaces when

the tube is pressed, whereas irregular holes are produced in the tubes now in use. As a result of this there is less chance of the vapors being directed against the head. Furthermore, the tie string 5 may be applied to this form of tube much quicker than in the plain tubes heretofore used. This outer tube is adapted to be used either in conjunction with the inner tube herein described or it may be sold separately for its individual advantages.

The inner tube, which is shown in Figures 3 and 4, consists of a corrugated cylindrical body 7 preferably formed of paper or card-board stock or other material capable of absorbing moisture, and the corrugations 8 of this tube extend lengthwise thereof. Preferably, this tube consists of a flat sheet of corrugated material 9 as is shown in Figure 5, which is adapted to be rolled into the tube shown in Figures 3 and 4, at the time it is being applied to the outer tube, in order that it may fit the latter or fit other size tubes. The sheet 9 may be folded in circular form with the edges overlapping as shown in Figure 4, so that overlapping corrugations will fit within each other as shown at 10 and thus lock the sheet in tubular form. The material or chemical for treating the hair is applied to the inner side of the corrugated tube 7 and in Figures 3 and 5, I have shown this material 11 applied within the grooves of the corrugations for a portion of the length of the tube. This material, which may be a paste containing borax or which may be any of the other materials used for permanent waving, is preferably spread over the inner surface of the sheet 9 as shown in Figure 5 so that it lies within the grooves of the corrugations and when the tube is rolled into cylindrical form as shown in Figures 3 and 4 the chemical material will lie inside the tube 7 and be presented adjacent to or against the lock of hair.

The corrugated tube 7 is inserted within the outer tube 4 so that it encircles the curler with the lock of hair and it is placed so that the portions carrying the treating material 11 immediately surround the lock of hair as shown in Figure 2. Generally, the inner

tube is inserted in the outer tube and both are applied over the lock of hair at the same time and it is customary to dip the tubes in water to wet the chemical material and supply the necessary moisture. Where smooth cylindrical inner tubes have been used as heretofore, it was necessary to hold the tubes in the water for a few seconds or else the chemical was not sufficiently moistened. In the present case when the tubes are inserted in the water the latter not only flows onto the chemical but it also passes into the spaces formed between the inner and outer tubes due to the spacing caused by the corrugations 8 and as a result both inner and outer surfaces of the inner tube 7 are very quickly moistened and the inner tube picks up a greater quantity of moisture than heretofore even though the tubes are immersed in the moisture for a very brief moment. This is a decided advantage because it insures sufficient moisture for operation. The grooves or the corrugations of the inner tube are sufficient to hold the chemical until the tube is put into use without other means for holding it and as there is nothing between the chemical and the hair when the tube is in use the action of the chemical is both quick and reliable. Both forms of tube are inexpensive to make.

Having described my invention, what I claim is:

1. A device for use in producing permanent waves in hair, including a cylindrical body, of absorbent material, adapted to enclose a lock of hair, and an inner, cylindrical body of compressible, absorbent material within said first body, said inner body having corrugations extending lengthwise thereof to form spaces between said inner and outer body.

2. A device for use in waving hair including a cylindrical body of absorbent material having corrugations and hair treating material disposed within the grooves of said corrugations on one side of said body.

Signed at the city, county and State of New York, this 29th day of October, 1924.

FRANÇOIS RENÉ MARCEL.
